UNITED STATES PATENT OFFICE.

JOHN S. ADAMS, OF ELGIN, ILLINOIS, ASSIGNOR TO THE DETROIT IRON TOWER COMPANY, OF DETROIT, MICHIGAN.

SKELETON TOWER.

SPECIFICATION forming part of Letters Patent No. 297,335, dated April 22, 1884.

Application filed October 12, 1881. Renewed March 17, 1884. (No model.)

To all whom it may concern:

Be it known that I, JOHN S. ADAMS, of Elgin, in the county of Kane and State of Illinois, have invented certain new and useful 5 Improvements in Towers; and I do hereby declare that the following is a full, clear, and exact description thereof, reference being had to the accompanying drawings, and to the letters of reference marked thereon, which form 10 a part of this specification.

This invention relates, mainly, to the application of elevators to skeleton towers, being primarily intended to provide means for reaching electric lamps supported at the summit of 15 a tower of this description for the purpose of dressing or repairing them. The elevator and its ways or guides are herein shown as being located on the tower interior, and as embracing certain features of construction and cer- 20 tain combinations with other parts peculiar to this situation. So far as relates to the construction of the guides and other parts, it is immaterial whether the carriage is employed for an attendant or it is used to carry a lamp 25 or lamps.

To these and other ends that will be stated the invention consists in the several features of construction and in various combinations of devices hereinafter fully set forth, and 30 designated in the claims.

In the accompanying drawings the invention is shown as applied to a skeleton tower of, say, from one hundred to five hundred feet in height, and suited to the support of an 35 electric light.

The tower may be supposed to be constructed of tubular iron having connections of cast-iron.

Figure 1 shows the base-section of a triangular skeleton tower of the general description set forth in other patents granted to me. Fig. 2 is a perspective view of the upper portion of the tower, showing devices for suspending the elevator and for the attachment of the upper-landing frame. Fig. 3 is a horizontal section of the tower above the lower elevator-landing, and showing an elevator passenger-cab lowered. Fig. 4 is a vertical transverse section of the frame of the lower elevator-landing, illustrating the use of one of the

transverse bars of said frame as the separating-bar for the elevator guide-ropes, and as being also attached to the weight by which said ropes are held taut. Fig. 5 is a detail showing a safety-clutch applied to the lifting 55 mechanism of the cab and adapted to operate in combination with the yielding or flexible ropes by which the cab is guided. Fig. 6 is a detail view, showing the elevator-pulley in side elevation, together with one of the inclined standards supporting the same and adjustable bearing for the pulley.

A represent the uprights or posts of a triangular tower, and B B the system of cross-ties and braces which join the uprights to form 65 a hollow skeleton structure of triangular pyramidal form.

C C' are rods connected with the upper extremities of the uprights A, and inclined upward and inward therefrom to converge in the 70 axis of the tower, forming, as here shown, a tripodal support for the mast A, which sustains and may represent the lamp or lamps. Said rods also, as here illustrated, form a suitable support for the elevator and its guides. 75

D is the elevator-carriage, which in this instance is shown as a passenger-cab. D' is its suspending-rope.

E E' are the rope or rod guides for the cab D.

E' is a bar from which the ropes E are im- 80 mediately suspended.

E' is a second bar, located at the lower end of the ropes E, by which the latter are held at a proper distance apart.

F is a special weight attached to the bar E', 85 by which the ropes E are held taut.

G is a raised platform or landing leading to the elevator-cab.

H is a frame for a landing and surrounding rail at the top of the tower. The upper 90 ends of the tower-uprights are connected by horizontal ties BB', which prevent their spreading, being joined by means of suitable "fittings," A'. The feet of the converging inclined standards C rest upon the uprights A, being 95 therewith joined, as here shown, by means of the transverse bars C' and the rather widely-branched fittings C', which join with the connections A'. At their upper ends the rods C unite in a fitting, C', which is also constructed 100

to receive and sustain the central mast, A². (Shown broken off in Fig. 2.) The object of the branched form of the connections C⁴, as herein shown, is to more firmly and widely support the bars C³, which pass through the former, as seen in Fig. 2, and which bars are extended to form supports for a landing and its surrounding guard-rail H. The platform of the landing will consist, preferably, of iron tubes suitably joined and secured, and arranged to rest upon the bars C³; but said platform may consist of planks or slats arranged and secured in place in any suitable manner. One of the inclined standards, as C', is made bifurcated, as clearly seen in Fig. 2, for the purpose of supporting the pulley C² between its legs c c, said legs having fitted and secured thereto the bearings c' for the pulley-shaft. A branched three-way casting, c', connects the legs c c at their upper ends, and a short single rod or tube joins said casting with the central elevated casting, C². The pulley C² will be arranged to suspend the cab D accurately in the axis of the tower. From and beneath the casting C² the transverse horizontal bar E' is supported, from the ends of which depend the ropes or rods E E, intended to serve as guides for the cap D.

Near the bottom of the tower, as seen in Fig. 1, a landing and walk, G, is provided at a suitable height to allow passage beneath it leading from the center of the tower to one of the uprights A, with which its outer end is secured. When of considerable length, as will usually be the case in towers of great altitude, said walk may be strengthened by a truss. In this case it is shown as having trussed guard-rails G', and also as having a suspended truss, g g', of the sectionally-triangular shape shown in Fig. 4. One of the transverse frame-pieces of this landing structure, as E', Fig. 4, gives attachment to the lower ends of the guide-ropes E, operating with the elevated bar E' to hold them parallel with each other and in the same plane. Said ropes E, when thus connected, serve to sustain the inner end of the landing G and obviate the use of supports beneath it at this point.

In lofty towers the expansion and contraction of the ropes E from exposure to changes of temperature or other influences will be considerable. Since it is desirable to hold said ropes uniformly taut, it is therefore necessary that the means by which this is done shall be yielding.

In the case of skeleton towers constructed of tubular iron, as may be supposed to be the case in the drawings, the long platform G will rise and fall as the ropes E expand and contract to practically meet this condition without the provision of hinged connections of such platform with the upright A; but, if preferred, such hinged connection may be provided. When for any reason it is not desirable to connect the platform with the guides E, the bar E' may be guyed to prevent rotation,

and the desired tension of the guide-ropes may be obtained from the use of a special weight, (shown at F;) and should the platform, when connected with the ropes, be of insufficient weight, the special weight F may be added thereto and applied at any suitable point for the purpose.

The weight F or the platform G, connected as described, is intended to represent any form of yielding force applied to the guide-ropes E and adapted to hold them taut by a practically uniform strain. Guys g² hold the inner end of the platform G in place laterally, and any suitable stair, permanent or removable, may be provided for reaching said platform from the ground.

For the purpose of checking the fall of the cab or carriage should the lifting-rope D' break, the lifting-bar D² of the cab is apertured at its ends to surround the guide-ropes E, and the clamp-bars D³ are applied in the usual or any approved manner, so as to be thrown out by the spring D⁴ when released into bearing upon the ropes E at d³. Said clamp-bars D³ are here shown as being severally pivoted to the lifting-bar at d², and as having loose sliding connection with the center piece, d⁵, as seen at d⁶, upon which the spring D⁴ immediately bears. The pivotal points d² and the bearing end faces d³ of the clamping-bars D³ are arranged in such relation, as indicated, that the latter will first throw the ropes E outward against the ends d' of the lifting-bar D², and will continue thereafter to bite the rope under strain from the falling cab until the latter is arrested.

While the general construction and mode of applying the clamping-bars D³, as shown in the drawings, is not materially different from those seen in elevators having rigid or fixed guides, it is obvious that, in combination with the yielding and flexible guides E and with the opposing support afforded by the ends d' of the lifting-bar D², an entirely new action is obtained, dependent on the yielding character of the guides E. The opposing bearings d' d' may of course be transposed, if desired.

As will be seen in Fig. 2, the fittings C⁴ are screw-threaded into the fittings A'. By this means the converging bars C may be adjusted to suspend the cab and its guides accurately in the center of the tower. If preferred, the threaded projections of the fittings C⁴ may rest loosely in the fittings A', and be provided with nuts which rest on the latter, and which allow of the adjustment of the legs C at any time, if found desirable or necessary, after the tower is completed. In such adjustment the rods C³ rotate in the fitting C⁴, or the foot-pieces of the standards may rotate on said rods.

A familiar mode of operating the elevator is only suggested in the drawings by the rope D', trained over the pulley C²; but other modes may be employed without departure from my invention. For example, the cab may be raised and lowered by known devices worked

by the occupant and operating in connection with the guides E, or in connection with a third rope or bar, also suspended and stationary. The use of such devices would dispense with the trained hoisting-rope D' and the special devices by which the pulley C² is sustained, but would not effect the operation of parts retained.

Obviously a spring may be employed to give an automatic tension to the guides E, substantially like but less perfect than the weight F. It is also plain that a spring or weight for this purpose may be connected with the guides at their upper ends, if, for any reason, such construction be preferred, the lower ends of said guides being fixedly held.

I claim as my invention—

1. The combination of a tower, an electric lamp supported thereby, and an elevator mechanism placed in the interior of the tower, by which an attendant may reach the lamp, substantially as described.

2. In combination with the tower-uprights and the inclined standards C, the duplex standard C' and the pulley C², mounted upon the legs c c of the latter, substantially as and for the purposes stated.

3. In combination, the duplex leg C', pulley C², and bearings c', adjustably secured to the legs c c, substantially as described, and for the purposes set forth.

4. In combination with the three or more converging standards forming the apex of the tower, as described, the mast A² and a suitable connecting-piece, C³, which joins the standards and supports the mast, substantially as and for the purposes set forth.

5. In combination with the uprights A and the inclined standards supported thereby, adjustable connections joining the standards with the uprights, substantially as described, and for the purposes set forth.

6. In combination with the uprights A and the inclined standards, the branched fittings C⁴, and horizontal rods C⁵, extended to give support to a landing, substantially as described.

7. In combination with the hollow tower, guides E for a cab, suspended from the top of

the tower, means for securing the guides E at their lower ends, and means for holding them at a suitable and equal distance apart at both their ends, substantially as and for the purposes set forth.

8. In combination with a tower and an elevator cab or carriage, the suspended flexible guides E and means for holding said guides in practically uniform tension materially greater than is due to their weight, which means automatically yield with the expansion and contraction of the said guides, substantially as described.

9. In a tower, the combination, with suspended elevator-guides E, subject to expansion and contraction, of a weight suspended thereby clear of the ground, whereby a practically uniform tension is maintained upon said guides materially greater than that due to their own weight, while permitting them to expand and contract, substantially as described.

10. In combination with a skeleton tower, provided with an interior elevator, the platform G, forming a lower landing from which access may be had to the elevator cab or carriage, and located at a suitable elevation to allow passage beneath the same, substantially as described.

11. In combination with the suspended cab-guides E, the platform G, suitably supported at its outer end, and supported at its inner end from the guides E, substantially as described.

12. In combination with the flexible cab-guides E, the cab provided with clamping-bars D³, arranged and actuated to bear upon the guides when the lifting-rope breaks, and fixed opposing bearings d', whereby the ropes are first more or less deflected and then grasped, substantially as described.

In testimony that I claim the foregoing as my invention I affix my signature in presence of two witnesses.

JOHN S. ADAMS.
